INVENTOR,
William Evans,

BY J. Walter Bingley,

ATTACHMENT

UNITED STATES PATENT OFFICE.

WILLIAM EVANS, OF PHILADELPHIA, PENNSYLVANIA.

MACHINE FOR TREATING HIDES OR SKINS.

SPECIFICATION forming part of Letters Patent No. 484,147, dated October 11, 1892.

Application filed June 16, 1892. Serial No. 436,897. (No model.)

To all whom it may concern:

Be it known that I, WILLIAM EVANS, a citizen of the United States, residing at the city of Philadelphia, in the county of Philadelphia and State of Pennsylvania, have invented certain new and useful Improvements in Machines for Treating Hides or Skins, of which the following is a specification.

My invention relates to an improved machine for fleshing, scudding, cleansing, striking out, slicking, skiving, frizzing, unhairing, laying out hides, skins, or leather in which use is made of a cutter or hide-dressing cylinder, a feed-apron or endless band and its complemental guide-rolls, a work-roller intermediate of said guide-rolls for conducting the feed-apron or band into proximity with the cutter or hide-dressing cylinder, and a pressure-roll for guiding the feed-apron away from the cutter or hide-dressing cylinder.

The principal objects of my present invention are, first, to avoid the formation of ridges or cutter-marks upon the surface of the hide or skin; second, to present the hide or skin to the knives or cutters of the hide-dressing cylinder in such manner that sufficient clearance is afforded without filing off the rear edges of the cutters; third, to simplify the construction, enhance the efficiency, and increase the output of the machine; fourth, to provide means that may be readily brought into operative position for sharpening or otherwise grinding the cutter or hide-dressing cylinder, and, fifth, to provide a removable housing for normally inclosing or concealing the cutter or hide-dressing cylinder.

My invention, stated in general terms, comprises a machine of the type recited having appliances for shifting the axis of the work-roller both horizontally and vertically in respect to the axis of the cutter or hide-dressing cylinder with or without a pressure-roll susceptible of radial adjustment in respect to the axis of the work-roller.

My invention further comprises a machine for treating hides or skins, provided with a hide-dressing cylinder, a feed-apron, and rolls for deflecting the feed-apron from the axis of the cylinder to afford clearance for the cutting edges or blades thereof.

My invention further comprises the im-

provements in machines for treating hides or skins, hereinafter described and claimed.

The nature, scope, and general characteristic features of my invention will be more fully understood from the following description, taken in connection with the accompanying drawings, forming part hereof, and in which—

Figure 1 is a view, partly in side elevation and partly in section, of a machine for treating hides or skins embodying features of my invention. Fig. 2 is an end elevation of the same, and Fig. 3 is a diagrammatic view illustrating the deflection of the feed-apron and the clearance afforded the knives or cutters of the cutter or hide-dressing cylinder.

In the drawings, *a* is the main frame of the machine.

b is a cutter or hide-dressing cylinder preferably mounted at the top of the main frame and journaled in boxes *b'*, that are susceptible of being adjusted in a vertical direction through the slots or ways *b*² by means of hand-screws *b*³.

c is a housing adapted to normally cover and conceal the cutter or hide-dressing cylinder *b*. In the present instance this housing *c* is adapted to be turned about a suitable hinge or joint *c'* (toward the left in Fig. 1) into position for exposing the cutter or hide-dressing cylinder.

d is a grinder journaled in twin rocker-arms pivotally connected with the opposite sides of the main frame *a* and adapted to be swung into position for sharpening the cutting-edges of the hide-dressing cylinder *b* after the latter has been uncovered by the removal of the housing *c*.

d' are sectors and complemental set-screws for maintaining the grinder *d* in operative position.

e is an endless belt or feed-apron adapted to travel around guide-rolls *f* and *f'*. The guide-roll *f* is journaled in suitable brackets or boxes *f*², carried by the main frame *a*, and the guide-roll *f'* is journaled in suitable blocks *f*³, working in ways *f*⁴, cut or otherwise formed in the opposite sides of the main frame *a*.

*f*⁵ are hand-screws for shifting the blocks *f*³ in a horizontal direction in order to tighten or loosen the belt or apron *e*, as may be required.

g is a positively-driven counter-shaft provided with two sets *g*³ and *g*⁴ of complementary fast and loose pulleys for imparting rotary motion to the grinder *d* and guide-roll *f* through the intervention of suitable belts *g*³ and *g*⁴ and of two sets *g*⁵ and *g*⁶ of complementary fast and loose pulleys applied to the axes of the guide-roll and of the grinder *d*. The counter-shaft *g* and the axis of the cutter or hide-dressing cylinder *b* are respectively provided with two fast pulleys and one loose pulley intermediate of the fast pulleys, whereby rotary motion in one direction may be imparted to the hide-dressing cylinder *b* through the intervention of a belt *h* and in a reverse direction through the intervention of a crossed belt *h'* for purposes hereinafter explained.

i is a work-roll journaled at its opposite extremities in journal-boxes *i'*, that are afforded a range of vertical adjustment in ways *i*², formed in blocks *i*³, that are afforded a range of travel in a horizontal direction through guides *i*⁴, formed in the main frame *a*, so that the axis of the work-roll *i* is susceptible of both a horizontal and a vertical adjustment for purposes to be presently described.

j is a pedal-lever frame pivotally connected with the opposite sides of the main frame *a* and adapted to shift the boxes *i'* upward or downward through the intervention of links *j*¹, that are connected at the lower extremities thereof with the pedal-lever frame. The upper extremities of these links work in slots *j*² in the main frame *a* and in the blocks *i*⁴ and are adapted to engage the boxes *i'*, the object being to afford the blocks *i*⁴ a range of play in a horizontal direction.

k are hand-screws engaging suitable tapped apertures *k'* in the main frame *a* and connected with the blocks *i*⁴ by means of swivel connections *k*², so that the rotation of these hand-screws effect the adjustment of the boxes *i'* and blocks *i*⁴ in a horizontal direction.

l is a pressure-roll journaled at its opposite extremities in journal-boxes *l'*, that are afforded a range of adjustment in ways *l*², cut or otherwise formed in the main frame *a* and disposed radially, or substantially so, in respect to the axis of the work-roll *i*.

*l*³ are hand-screws for adjusting the journal-boxes *l'*.

The peculiar relative adjustments of the work-roll *i* and pressure-roll *l* in respect to the operative portions or blades of the hide-dressing cylinder *b* are important, because they enable the flesh and hair sides of a hide or skin to be finished perfectly smooth and even and free from cutter marks or ridges. The disposition of the rolls *i* and *l* in respect to the periphery of the cutter or hide-dressing cylinder constitutes a material part of my invention and is productive of beneficial results, because the roll *i* serves to lead the feed-apron *e* into position for presenting the hide or skin to the cutting-edges, Fig. 3, of

the knives or cutters of the cylinder *b*, and the roll *l* serves to deflect the feed-apron away from the axis of the cylinder *b* in such manner that a clearance is afforded, as at *x'*, for the rear edges *x*² of the cutters or knives, thus obviating the necessity for filing away the rear edges of the cutters or knives of the hide-dressing cylinder *b* and enabling the cutters to be sharpened by means of the grinding-wheel *d*.

In use the cutter or hide-dressing cylinder *b* and guide-roll *f* are caused to rotate in the direction indicated by the arrows in Fig. 1 through the instrumentality of the belts *h*³ and *g*⁴ and their complementary pulleys, and the rotary motion of the guide-roll *f* causes the feed-apron *e* to travel in the direction indicated by the arrow. A hide or skin is then placed upon the feed-apron *e* and by it carried into range of the operative edges *x* of the knives or cutters of the hide-dressing cylinder *b* and then out of range of the same, as shown in Fig. 3, so that a portion of the surface of the hide or skin is removed or cut away and a sufficient clearance is afforded, as at *x'*, for insuring the successful operation of the knives or cutters of the cylinder *b*. Of course the depth of the cut effected by the hide-dressing cylinder *b* will be subject to the control of the attendant in charge. This result is accomplished in the hereinabove-described machine by means of the pedal-frame *j*, that serves to shift the work-roll *i* upward or downward, thus causing the apron *e* to carry the hide nearer to or farther away from the center of the hide-dressing cylinder *b*, with the result that the depth of the cut effected by the latter is increased or diminished, as required.

The smoothness or evenness of the surface of the hide or skin after it has been operated upon by the hide-dressing cylinder *b* in the manner above described depends upon the distance that it traverses in range of the cutting or knife edges of the cylinder *b* and also upon the direction and extent of its travel in respect to the periphery of the cylinder *b*. In the hereinabove-described machine the apron may be caused to conduct the hide into range of the cylinder *b* at any required point and to maintain the same in range of the cylinder for any required time or distance within the limits of adjustment of the machine by shifting the work-roller *i* in a horizontal direction and the pressure-roller *l* in radial direction in respect to the axis of the work-roller *i* through the intervention of the hand-screws *l*³ and *k*. By these means the course or direction of travel of the apron *e* may be varied or adjusted in order to cause the hides or skins to be presented to the hide-dressing cylinder in the most advantageous position for affording sufficient clearance for the knives or cutters of the cylinder and for securing a clean drawing cut or stroke of the latter, whereby the filing off of the cutters is

obviated and the production of a smooth even surface of the hide or skin free from cutter marks or ridges is insured.

The rear edges of the cutters or knives of the hide-dressing cylinder need not be cut away, because sufficient clearance, as at x' , is afforded by reason of the deflection of the feed-apron, (shown at x^3 in Fig. 3,) so that the cutting-edges of the cutter or blades may be sharpened in the following manner and without the use of files and other similar tools: The housing c is turned toward the left into position for exposing the hide-dressing cylinder b and the grinder d is swung toward the left and adjusted into operative position by means of the sector and its complemental set-screws, whereupon the grinder is caused to revolve in the direction indicated by the arrow in Fig. 1, and the hide-dressing cylinder is caused to revolve in a reverse direction through the instrumentality of the crossed belt h' , with the result that the cutters or operative edges of the hide-dressing cylinder are sharpened and ground.

Having thus described the nature and objects of my invention, what I claim as new, and desire to secure by Letters Patent, is—

1. A machine for treating hides or skins, provided with a hide-dressing cylinder, a feed-apron and its complemental guide-rolls, a work-roll disposed intermediate of the guide-rolls and afforded a range of horizontal and vertical adjustment in respect to the axis of the hide-dressing-cylinder, a pressure-roll susceptible of radial adjustment in respect to the axis of the work-roll, and means for shifting said work and pressure rolls, substantially as and for the purposes set forth.

2. In a machine for treating hides or skins, a hide-dressing cylinder, a feed-apron, a ver-

tically and horizontally adjustable work-roll, and a pressure-roll susceptible of adjustment with respect to the work-roll and to deflect the feed-apron from the hide-dressing cylinder, substantially as and for the purposes set forth.

3. In a machine for treating hides or skins, a hide-dressing cylinder, a feed-apron, a roll for conducting the apron into proximity to the cutting-edges of the cylinder, and a roll for deflecting the apron from the axis of the cylinder to afford clearance to said cutting-edges, substantially as and for the purposes set forth.

4. In a machine for treating hides or skins, a hide-dressing cylinder, and a feed-apron for conducting the work into range of the cutting-edges of the knives or cutters of the cylinder and out of range of the rear edges of the knives or cutters of the cylinders, substantially as shown, and for the purposes set forth.

5. A machine for treating hides or skins, provided with a hide-dressing cylinder, a feed-apron, and means for deflecting the feed-apron from the axis of the cylinder to afford clearance for the cutting edges or blades thereof, substantially as and for the purposes set forth.

6. A machine for treating hides or skins, provided with a hide-dressing cylinder, a feed-apron, and means susceptible of vertical and horizontal adjustment for bringing said apron into proximity to and away from the knives or cutters of said cylinder, substantially as and for the purposes set forth.

In testimony whereof I have hereunto set my signature in the presence of two subscribing witnesses.

WILLIAM EVANS.
